CLAIM

The ornamental design for a wristwatch and strap, as
shown and described.

DESCRIPTION

FIG. 1 is a front and right side perspective view of a
wristwatch and strap showing my new design;

FIG. 2 is a rear elevational view, with the fastening
portion being eliminated for ease of illustration;

FIG. 3 is a left side elevational view;

FIG. 4 is a front and left side perspective view; and

FIG. 5 is a top plan view thereof, the bottom plan view
being a mirror image.

FIG. 1

FIG. 2

FIG. 3

FIG. 4

FIG. 5
